CLAIM

The ornamental design for a scanner device, as shown and described.

DESCRIPTION

FIG. 1 is a first perspective view of a scanner device, taken from the back;

FIG. 2 is a second perspective view of the scanner device, taken from the front;

FIG. 3 is a front view of the scanner device as shown in FIG. 1;

FIG. 4 is a back view of the scanner device as shown in FIG. 1;

FIG. 5 is a right-side view of the scanner device as shown in FIG. 1;

FIG. 6 is a left-side view of the scanner device as shown in FIG. 1;

FIG. 7 is a top view of the scanner device as shown in FIG. 1; and,

FIG. 8 is a bottom view of the scanner device as shown in FIG. 1.

The broken lines shown as dashed lines represent features of the scanner device which form no part of the claimed design.
